his Attorney.

UNITED STATES PATENT OFFICE.

CHARLES M. FERRELL, OF UTICA, NEW YORK.

CAR-COUPING.

SPECIFICATION forming part of Letters Patent No. 349,488, dated September 21, 1886.

Application filed May 28, 1886. Serial No. 203,538. (No model.)

To all whom it may concern:

Be it known that I, CHARLES M. FERRELL, a citizen of the United States, residing at Utica, in the county of Oneida and State of New York, 5 have invented certain new and useful Improvements in Car-Couplings, of which the following is a full, clear, and exact description.

This invention relates to automatic coupling devices for cars where the link is held in position to engage the draw-heads—as, for example, where the link is already fastened in one draw-head and it is desired to connect another car to it.

The object of the invention is to simplify 15 the construction of parts, avoid the use of springs, and to secure the entrance of the link into the draw-head at very short range of movement. A further object is to provide uncoupling mechanism which will obviate the 20 necessity of a brakeman going between the cars to manually adjust the link or the coupling-pin.

With these objects in view my invention 25 consists in the construction of a car-coupling mechanism substantially as hereinafter particularly set forth and claimed.

In the accompanying drawings, in the several figures of which like parts are similarly 30 designated, Figure 1 is a vertical section of a draw-head of my invention with the parts in position to receive a coupling-link. Fig. 2 is a similar view with the link engaged. Fig. 3 is a front view; Fig. 4, a side view of the uncoupling device, and Fig. 5 a plan view of the 35 latter.

The letter *a* designates a draw-head having the usual draw-bar, *b*, and flaring mouth *c*. This draw-head is provided with a vertical wall, *d*, standing up from its upper side, and 40 adapted to bear against the front sill or beam of the car under compression of the usual spring to serve as a bumper. In the bottom of the draw-head a cavity or slot, *e*, is made, and on each side of this cavity and parallel 45 with it are arranged inclines *f*, which serve as directors, in connection with the rear curved wall, *a'*, of the draw-head, to insure the proper entrance of the link into the draw-head, and to the coupling devices, no matter from what direction it may come. In this slot *e* I secure a 50 peculiarly-shaped tumbler, *g*, using for this

purpose a pivotal bolt, *h*, passed transversely through the draw-head and through an elongated slot, *i*, in the tumbler, the said slot providing for the tumbler taking its bearing upon 55 the metal of the draw-head, and thus removing the strain from its bolt to the draw-head. This feature is important, in that it enables me to use a lighter bolt, and the bolt is not bent out of line, and so rendered difficult of 60 withdrawal when a new tumbler is to be inserted. This tumbler has a curved striking-surface, *j*, against which the link hits in entering, and also has the pin *k*, which engages the link, and against which the link draws. 65 In a slot or cavity, *l*, in the upper wall of the draw-head is arranged a dog, *m*, pivoted by a slot, *n*, upon a bolt, *o*, passed transversely through the draw-head. This slot permits the dog to bear against the draw-head, and so removes the strain from the bolt, as and for the 70 same purpose as in the case of the tumbler. This dog has a tail-piece, *b*, against which the pin *k* strikes to lift it and then passes behind it, and thereafter as the link is drawn upon the 75 said pin comes in contact with the inner face of said tail-piece, and is locked by it to retain the link on it (the said pin) until the dog is forcibly disconnected from it.

As will be observed from the construction 80 and arrangement of parts shown, there is but a minimum of movement allowed the link in my coupling, and hence there is little or no slack to be taken up when the train starts; hence I remove that source of damage hitherto 85 hitherto incident to couplings as commonly constructed.

The uncoupling mechanism I prefer to use 90 consists of a finger, *q*, provided with a squared transverse socket, as indicated by dotted lines, Fig. 5, which receives the squared ends of two 95 shafts, *r r'*, arranged upon the platform of the car over the draw-head, crosswise thereof and extending to the sides of the car. At their outer ends these shafts have hand-levers *s s'*, which are weighted at one end, so as to assist 100 the gravity of the finger in keeping it down. These hand-levers are provided with lugs *t t'*, which are adapted to be engaged with notched segmental racks *u u'* on the sides *v v'* of the car to positively hold said levers, and consequently the finger, in desired position. The finger *q*

is loosely engaged with the dog m , as seen in Fig. 2, and by raising and lowering said finger, by means of the hand-levers, the said dog is correspondingly operated. Now, if it be desired to operate the dog m from one or the other side of the car and the lever on the opposite side be engaged with the rack on that side, by simply pushing the lever on the operating side toward the side of the car the shaft $r' r'$ on that side will slip lengthwise in its bearings, and also in the socketed finger, and push against the shaft on the other side and move it longitudinally outward and disengage its lever from the rack, and so permit the finger to be operated. (See dotted lines, Fig. 5.) The guard-rails $w w'$ on the racks prevent the levers from being thrown entirely out of their bearings.

The link rests on the inclines f when in the draw-head, and as the preponderance of weight in the tumbler is below its pivot and toward the front said tumbler acts by gravity to discharge the link from the draw-head as soon as the pin k is disengaged from its dog. The dog also by gravity assumes the locking position, and hence needs no spring or other device to hold or send it there.

It will be seen that as soon as the link strikes the surface j of the tumbler said tumbler rotates on its pivot backward, and at the same time its pin k turns up and enters and engages the link. I use an ordinary open $\textcircled{O}$ (elongated O) link by preference.

In order to provide suitable abutting surface in the draw-head for the tumbler, I make a cavity, e' , in the mouth of the draw-head to receive the pin k when in the unlocked position, and upon each side of said cavity and between the inclines $f' f'$, I construct the abutments $f' f'$, which are curved on their rear faces to correspond with the heel g' of the tumbler on each side of the pin k , and against these abutments said heel bears when the coupling is in use for drawing. The strain or draft is thus placed upon the draw-head, instead of upon the bolt.

My coupling may be applied to cars without

any special rearrangement of their construction, and, all its parts being readily renewable by even the most unskillful, it can be applied and used very economically.

What I claim is—

1. A draw-head provided with a pivoted dog, and a pivoted tumbler, g , having a pin to engage the coupling-link, and an abutting surface which is struck by the entering link to rotate the tumbler and bring its pin into engagement with the link and with said pivoted dog in said draw-head, and abutments $f' f'$, against which said tumbler bears, substantially as described. 55

2. A draw-head, a tumbler pivoted in a cavity therein and adapted to bear against abutments $f' f'$ in the draw-head and provided with a link-engaging pin, and a dog co-operating with the pin of the tumbler to engage 65 and hold a coupling-link, substantially as described.

3. A draw-head provided with a tumbler, g , pivoted in a cavity therein and having a pin to engage the coupling-link, inclines arranged on the sides of and parallel with said cavity, abutments $f' f'$, against which the said tumbler seats itself, and a locking-dog to engage the pin of said tumbler, all combined substantially as described. 70

4. A car-coupling mechanism of the construction substantially as set forth, combined with uncoupling mechanism comprising a finger, q , longitudinally-movable shafts $r' r'$, to operate said finger, and levers $s' s'$, connected 80 to said shafts to operate them, substantially as described.

5. The draw-head provided with the abutments $f' f'$, combined with the pivoted tumbler adapted to bear against said abutments, 85 substantially as described.

In testimony whereof I have hereunto set my hand this 17th day of May, A. D. 1886.

C. M. FERRELL.
